John R. Meen
ATTORNEY

UNITED STATES PATENT OFFICE.

ALBERT A. E. STERZING, OF NEW YORK, N. Y.

STEAM-TURBINE.

1,338,708.

Specification of Letters Patent.

Patented May 4, 1920.

Application filed June 7, 1918. Serial No. 238,628.

To all whom it may concern:

Be it known that I, ALBERT A. E. STERZING, a subject of the King of Great Britain and Ireland, and resident of the city and county of New York and State of New York, have invented certain new and useful Improvements in Steam-Turbines, of which the following is a specification.

In my Letters Patent of the United States No. 1,281,224, dated October 8, 1918, is described a steam turbine engine whereof the rotor and stator elements are each provided with concentric series of facial action and reaction chambers constituted by $\square$ -shaped pockets having angularly-disposed inner wall portions, those of adjacent elements being oppositely positioned in relation to each other, and said chambers gradually increasing in size from the inner to the outer series, whereby steam introduced to the inner series expands circumferentially and radially outward through the successive chambers, flowing in a sinuous course from chamber to chamber and exerting a turning effort on the opposing surfaces presented by the semi-circular end walls of the succeeding series of pockets. The curved end walls of the co-ordinated pockets of the stator and rotor elements deflect the steam in a smooth and easy path to and upon the angular inner walls of the pockets, and such walls during their relative rotation tend similarly to direct the steam continuously from and between opposing pockets.

In the use of low-pressure steam in my said engine there is liability of the formation of cross or eddy currents within the pockets during the travel of the steam therein, which condition, when occurring, impairs the efficiency of the engine. The object of my invention is to overcome the objection mentioned, and to that end I provide each of the pockets with a central longitudinally-extending division portion which terminates short of the curved impact end of the pocket and thus provides two channels which divide the steam into inflowing and outflowing currents as it passes to and from the impact wall, as will be hereinafter described and claimed.

In the drawings—

Figure 1 is an elevation of parts of the stator and rotor elements of a steam turbine embodying my present improvement.

Fig. 2 is a transverse vertical section, as on the line 2—2 of Fig. 1.

Fig. 3 is a horizontal section, as on the line 3—3 of Fig. 2.

Fig. 4 is a face elevation of a portion of one of the pocketed elements of the engine. 60

Fig. 5 is a similar view, showing a slight change in the form of the pockets.

Fig. 6 is a sectional detail of one of the end heads of the stator and the adjacent member of the rotor, showing a modified 65 form of pockets.

Referring to the drawings, 11 designates parts of the end heads, and 12 one of the pocketed partition members of the cylinder; said head and partition member constituting 70 stator elements.

14 designates rotor members alternating with the stator members and keyed or otherwise secured to a central shaft 15. Each member of the stator and of the rotor (excepting the outer walls of the stator heads) is provided in each of its faces with a plurality of concentric series of pockets 29, those of each series being in uniform order of succession. Each pocket is $\square$ -shaped in 80 face view, the curved wall (a) thereof constituting a steam impact surface. The inner wall (b) of the pocket extends angularly outward from the inner or basal part of its impact surface to the corresponding surface 85 of the next succeeding pocket of the series, thus affording a continuous series of elongated steam reaction chambers having curved impact surfaces and angularly disposed directing surfaces. The angularity of 90 the chambers in one face of the member is reversely of that of the chambers in the other face thereof, and the rotor and stator members are so arranged that the chambers in the adjacent walls of the respective chambers are in opposite relation to each other and bridge or overlap, the circular walls 30 which separate the successive series of concentric chambers of each face bridging the proximate complementary chambers of the 100 adjacent face. (See Figs. 1 and 2.) The end heads of the stator are formed with angularly disposed reaction chambers in their inner faces only, but each of the internal members is provided with such chambers in both its faces, as above mentioned. 105

The steam admitted at the inner or central portion of the apparatus expands circumferentially and radially outward, flowing in a sinuous course from chamber to chamber 110 and continuously exerting a turning effort on the opposing surfaces presented by the

semi-circular end walls of the succeeding series of pockets, which pockets gradually increase in size from the inner to the outer portion of the apparatus in order to compensate for the progressive expansion of the steam, all as fully set forth in my previous application aforesaid.

According to my present invention I form in each of the pockets a central division wall 10 *c* which terminates short of the curved impact end of the pocket, so as to afford two parallel channels which extend longitudinally of the pocket and communicate with each other at the impact end of the latter. 15 Thus the steam in its course through and from each pocket flows along the inner channel to and against the impact wall and is thereby deflected into the other or outer channel of the pocket (as indicated by the 20 arrows in Fig. 4), whence it continues its outward travel to the pockets of the succeeding series. The steam current is thus partitioned in its passage through the several pockets, thereby obviating liability of cross 25 or eddy currents within the main portions of the pockets, particularly when the steam is of low pressure.

In Figs. 5 and 6 I have shown adjacent

portions of the impact surfaces of the rotor and stator members, respectively, as provided with lateral lips *d* which are designed to restrict to some extent the lateral flow of the steam.

I claim—

In a turbine engine, the combination with 35 a stator element having concentric series of facial reaction chambers constituted by D-shaped pockets having angular inner walls, thereby presenting curved impact and pressure surfaces and angular directing surfaces, said pockets also having division walls extending longitudinally thereof and terminating short of the curved impact and pressure surfaces of the respective pockets, of a rotor element having concentric series 40 of facial chambers corresponding in form with and bridging the adjacent chambers of the stator element, the directing surfaces of the adjacent chambers in the rotor and stator elements being in opposite relation to each 45 other, and said chambers gradually increasing in size from the inner to the outer series.

Signed at the city of New York, in the county and State of New York, this 6th day of June, A. D. 1918.

ALBERT A. E. STERZING.
